(57) CLAIM

The ornamental design for a pet collar, as shown and described.

DESCRIPTION

FIG. 1 is a front elevational view of a pet collar showing my new design;

FIG. 2 is a rear elevational view thereof;

FIG. 3 is a side view, taken from the left side of FIG. 1, the right side view being a mirror image thereof; and,
FIG. 4 is a top plan view thereof, the bottom plan view being a mirror image thereof.
